US00D757807S

(12) **United States Design Patent**
Patel et al.

(10) **Patent No.:** **US D757,807 S**
(45) **Date of Patent:** **** May 31, 2016**

(54) **DISPLAY SCREEN WITH GRAPHICAL USER INTERFACE**

(71) Applicant: **Microsoft Corporation**, Redmond, WA (US)

(72) Inventors: **Amish Patel**, Seattle, WA (US); **Larry Russell Butcher**, Seattle, WA (US); **Michael Tedesco**, Sammamish, WA (US)

(73) Assignee: **Microsoft Corporation**, Redmond, WA (US)

(**) Term: **14 Years**

(21) Appl. No.: **29/492,468**

(22) Filed: **May 30, 2014**

(51) LOC (10) Cl. **14-04**

(52) U.S. Cl. **USPC D14/492**

(58) **Field of Classification Search**

USPC D14/485-495; D18/27; D19/6; D20/11, D20/23, 27, 29, 37

See application file for complete search history.

(57) **CLAIM**

The ornamental design for a display screen with graphical user interface, as shown and described.

DESCRIPTION

The sole FIGURE is a front view of a display screen with graphical user interface showing our new design.

The broken line rectangle showing the display screen is included for the purpose of illustrating portions of the article and forms no part of the claimed design.

1 Claim, 1 Drawing Sheet
